UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL PRESS.

Application filed March 23, 1917, Serial No. 156,824. Renewed July 10, 1922. Serial No. 573,919.

To all whom it may concern:

Be it known that I, ERASTUS E. WINKLEY, a citizen of the United States, residing at Lynn, in the county of Essex and State of Massachusetts, have invented certain new and useful Improvements in Heel Presses; and I do hereby declare the following to be a full, clear, and exact description of the invention, such as will enable others skilled in the art to which it appertains to make and use the same.

This invention relates to machines in which heel stock, such as heels or heel-piles, or parts thereof, newly built of layers or lifts cemented together, are held under pressure during the setting or drying of the cement.

One object of the invention is to produce a heel-press of which the parts are so arranged as to permit the convenient introduction and removal of the heel stock, while at the same time the machine occupies a minimum space and does not obstruct the light in the room in which it is used.

To the foregoing end the machine of the present invention is provided with a series of heel-clamps, which are supported for movement in a horizontal plane, and the clamps are provided with upper and lower substantially horizontal heel-engaging members or jaws, the parts being so arranged that the heel stock may be introduced to and removed from the clamps horizontally, by movement in the plane of rotation of the clamps.

Another object of the invention is to provide for the convenient adjustment of the clamps according to the size of the heel stock to be operated upon. To this end the clamps are so constructed and mounted that they may all be adjusted simultaneously and in equal degree by a single operation.

Another object of the invention is to produce a heel-press of which the operation is controlled by, or in connection with, the act of manually introducing the heel stock. To this end the machine is provided with devices operating simultaneously, when the heel stock is so introduced, to initiate the cycle of operations of the machine, while the actuating-mechanism automatically ceases its operation upon the completion of such cycle.

Other objects of the invention, and the features of construction by which they are

attained, are set forth in connection with the following description of the illustrated embodiment of the invention.

In the accompanying drawings Figure 1 is a side-elevation of a heel-press embodying the present invention, with parts broken away to illustrate the construction more clearly; Fig. 2 is a detail-view showing part of the mechanism for opening the heel-clamps; Fig. 3 is a partial plan-view of the machine; Fig. 4 is a detail-view, in side-elevation, of the feed-table and parts immediately associated therewith; Fig. 5 is a plan-view, in section on the line 5—5 in Fig. 1; Fig. 6 is a detail-view, in elevation, of the clutch-mechanism through which the machine is actuated; Fig. 7 is a detail-view, partly in horizontal section, of part of the mechanism for rotating the clamp-carrier; and Fig. 8 is a detail-view, in elevation, of a part of the same mechanism.

The invention is illustrated as embodied in a heel-press in which an endless series of thirty-two heel-clamps are employed, arranged in a circle. Each clamp comprises upper and lower members or jaws 10 and 12 respectively. The upper jaws 10 are supported by an annular member 14 constituting a part of the clamp-carrier. These jaws are mounted with provision for a pivotal or rocking movement to accommodate the clamps to such angularity as may exist between the upper and lower surfaces of the heels. For this purpose the member 14 is provided with concaved seats 16 for each jaw, while the jaw is provided with convex bosses 18 which rest in the seats. A lug 20 projects upwardly from the jaw between the bosses and through a slot in the seat, and is secured loosely in place by a cross-pin. The lug slides freely in the slot to permit a rocking movement of accommodation in the clamp-jaw.

The lower jaw 12 of each clamp is movable towards and from the upper jaw to clamp and unclamp the heel. For this purpose it is mounted on a stem 22, which slides vertically in openings in upper and lower annular members 24 and 26 constituting parts of the clamp-carrier. A spring 28, surrounding each stem, is seated, at its lower end, upon the carrier-member 26, while its upper end presses against the clamp-jaw and tends to raise the latter, and thus to subject the heel between the jaws to a constant pressure suffi-

cient to force the layers of material closely together while the cement is drying. The carrier-members 24 and 26 are held rigidly in parallel relation by uprights 30 projecting from the member 26 and fixed, at their upper ends, to the member 24.

In order that the clamps may be opened by a minimum movement of the lower jaws, in opposition to the springs 28, the upper jaws are made adjustable towards and from the lower jaws, in accordance with the size of the heels to be operated upon. To permit this adjustment to be made simultaneously and equal for all of the upper jaws, it is accomplished by moving the carrier-member 14 vertically, while maintaining its parallel relation with the members 24 and 26. For this purpose the member 14 is provided with a series of inwardly projecting lugs 32 which are perforated to receive a series of vertical rods 34. Each rod is screw-threaded and passes through a correspondingly threaded opening in the carrier-member 24, while the lug 32 rests upon a collar 36 fixed on the rod. At its upper extremity each rod is provided with a head 38 engaging the upper surface of the lug. In this manner the carrier-member 14 is supported firmly at a fixed, but adjustable, distance above the member 24, and this distance may be adjusted by rotating the rods 34, for which purpose each of the heads 38 is provided, as shown in Fig. 3, with two sockets which may be engaged by a tool of suitable form.

In order that all of the rods 34 may be adjusted simultaneously and equally, each of the collars 36 is provided with sprocket-teeth about which a chain 40 passes. Rotation of any one of the rods 34, by the means just described, is transmitted through the chain to all of the other rods, and the clamps may, therefore, be quickly, conveniently and accurately adjusted.

The intermediate carrier-member 24 is provided with webbed spokes 42 which unite in a central hub arranged to turn upon a stationary vertical tube 44. This tube is fixed, near its lower end, in a column 46 rising from the bed-plate 48 of the machine. The hub of the carrier is supported upon a second hub 50, which turns about the tube 44 for a purpose to be described. To support the hub 50 and to facilitate the movement of the parts, a ball-bearing 52 is interposed between the hub 50 and the top of the column 46.

The carrier is moved intermittently, but always in the same direction, in order to bring the several clamps successively to a point where the heels are loaded and discharged. This intermittent movement is produced by ratchet-mechanism including a double or yoke-like lever 54, extending integrally from the hub 50. The carrier-member 24 is provided with a series of depend-

ing ratchet-teeth 56 spaced similarly to the heel-clamps, and the lever 54 carries, at its outer end, a pivoted pawl 58 which cooperates with these teeth, a spring 60 constantly pressing the pawl upwardly to maintain such operative engagement.

The lever 54 is actuated by cam-mechanism comprising a sleeve 61 which is mounted to turn freely on a rod 62 fixed horizontally on the frame of the machine. A cam 64, fixed on and rotated by the cam-sleeve 61, engages a roller 66 on one arm of a bell-crank lever 68, and this lever is pivoted loosely on a rod 70, mounted in stationary position on the frame of the machine. The upper arm of the lever 68 is connected, by a universal joint 72, with one end of a spring-housing 74, while the rod 76 slides through an opening in the other end of the housing and is connected, by a universal joint 84, with the lever 54 (Fig. 7). The inner end of the rod 76 is provided with a head 78, and a compression spring 80, enclosed within the spring-housing, acts against this head and against the right-hand end of the housing. The expansion of the spring is limited by stop-nuts 82 on the rod.

The cam acts once during each rotation to swing the upper arm of the lever 68 to the left, thus rocking the lever 54 in a clockwise direction through a space approximately equal to that between two of the ratchet-teeth 56, and in this manner the carrier is turned sufficiently to remove one heel-clamp from the loading-point and bring the next clamp in succession to that point. The mechanism including the spring 80 provides a yielding connection, which avoids injury to the machine in case the rotation of the clamp-carrier encounters any unusual resistance, owing to the jamming of the machine or any other accidental cause.

A buffer is provided for arresting the rotative movement of the clamp-carrier at the proper point and without shock. This buffer includes a frame of generally triangular form, comprising an upright member 86 and two inclined members 88 and 90 (Figs. 1 and 5). At its lower angle the buffer-frame is pivoted upon one end of the rod 62. The upper part of the frame is bored to receive a stop-plunger 92 of which the upper end cooperates with the ratchet-teeth 56. The lower end of the plunger is fixed to a slide-block 94, which moves in a vertical guide-way 96 forming part of the frame-member 86. A spring 98 presses upwardly against the slide-block and tends to hold the stop-plunger in position for engagement with the ratchet-teeth, as shown in Fig. 1.

A slight lateral yielding movement of the plunger, when engaged by a ratchet-tooth, is provided by the pivotal mounting of the buffer-frame. At the junction between the frame-members 88 and 90 a socket 100 is

provided which loosely embraces the end of the rod 70, and a spring-pressed plunger 102, arranged to slide in the frame-member 88, engages the rod and maintains the parts 5 normally in the position of Fig. 1. When the plunger 92 is engaged by a ratchet-tooth the momentum of the carrier is absorbed by a rocking movement of the buffer-frame about the shaft 62, which is permitted by the 10 momentary yielding of the plunger 102, the parts being restored immediately thereafter to normal position by the action of the spring 104 which controls the plunger.

In order to prevent recoiling from the 15 stop-plunger 92 a pawl 106 is pivoted, at the upper end of the buffer-frame, in position to engage the rear surface of the same ratchet-tooth which is arrested by the stop-plunger. This pawl 106 is yieldingly supported by 20 a spring-plunger 108, so that it does not interfere with the advancing movement of the ratchet-teeth into engagement with the stop-plunger.

Before each advancing movement or rotation of the carrier it is necessary to disengage the stop-plunger from the ratchet-tooth with which it is in contact, and this is accomplished by cam-mechanism which momentarily retracts the stop-plunger. By means 25 of a pin 110 the slide-block 94 is connected with the upper end of a link 112, of which the lower end is pivoted to a bell-crank lever 114 (Figs. 1 and 5). This lever is mounted on a stationary pivot-stud 116 on the buffer 30 frame member 90. The lower arm 118 of the lever 114 cooperates with a pin 120 which projects from the cam 64, this pin being so located that, at the proper point in the cycle of operations of the machine, it encounters 35 the arm 118 and acts, through the connections just described, to draw the stop-plunger 92 downwardly just before the lever 54 is actuated to rotate the clamp-carrier. The continued movement of the pin 120 disengages 40 it from the arm 118, and the stop-plunger is thus permitted to rise again, under the influence of the spring 98, in time to arrest the movement of the next ratchet-tooth 56.

50 After the arrival of each heel-clamp at the loading position, it is necessary to move the lower clamp-jaw downwardly to release the heel which is held in the clamp, and for this purpose cam-actuated mechanism is provided. On the lower end of each stem 22 is fixed an inwardly-projecting arm 122 (Fig. 2), and each of these arms, in turn, cooperates with a retractor 124. This retractor is 55 in the form of an upright arm integral with a vertical sleeve 126 (Figs. 1 and 2), the upper extremity of the arm being provided with a lug 128 which overhangs the arm 122 of that clamp which is at the moment at the loading-point. The sleeve 126 slides vertically 60 on a guide-rod 130 mounted on the

base-plate of the machine, and the sleeve is pivoted to the forked end of a cam-lever 132, which is pivoted on a rod 134 fixed on the frame of the machine. The other arm 136 of the lever carries a roller 138 which is 70 actuated by a cam 140 on the cam-sleeve 61. This cam is so formed that upon the arrival of each clamp at the loading-point the retractor 124 is drawn downwardly, thus engaging the arm 122 and opening the 75 clamp. The parts are then retained in this position until the next cycle of operations of the machine, whereupon the mechanism acts to release the clamp-jaw prior to the next partial rotation of the clamp-carrier. 80

The loading and unloading of the clamps is facilitated by the provision of a loading-table 142 (Figs. 1, 3 and 4). This table is fixed, in horizontal position, upon an arm 144 projecting rigidly from an upright frame-member 146 which is connected, at its lower end to the base-plate of the machine. The loading-table is set at the level of the upper surface of the lower clamp-jaw, in the retracted position of the latter, 90 so that a heel lying upon the feed-table may be slid directly, by horizontal movement, into the space between the clamp-jaws, by movement approximately radial with respect to the clamp-carrier. 95

The pressed heel is ejected from each clamp-carrier, prior to the introduction of a fresh or green heel, by an outward movement opposite to that by which the fresh heel is introduced. In order to divert the 100 heel so ejected laterally from the feed-table a deflector is employed, in the form of a vertical plate 148 which occupies normally a diagonal position above the feed-table, as shown in Fig. 3. This plate is provided, at 105 one end, with a depending stud 150 by which it is pivoted to the outer end of the feed-table, and a spring 154, coiled about the stud, is connected at one end to the table, and at the other end to a collar 152 on the stud 110 (Fig. 4). This spring tends to hold the deflector in its normal position, which is determined by a stop-lug 156 depending from the deflector and engaging the edge of the feed-table. The pivotal arrangement just 115 described is provided in order that the deflector, after performing its function, may be swung aside from the feed-table in order to avoid obstruction to the movement of a fresh heel into the heel-clamp. 120

To facilitate the introduction of the heels in correct position in the heel-clamp, a gage-member is provided, which acts also as an ejector to remove the pressed heels. This 125 combined gage and ejector-member comprises a flange 158, shown in dotted lines in Fig. 3, on the outer end of a horizontal plate 160. The plate is adjustably fixed on the upper surface of a slide 162, which is arranged to move horizontally in a substan- 130

tially radial direction with respect to the clamp-carrier. The slide 162 is provided with sleeves 164 and 166, connected by an integral yoke 170 and arranged to slide upon a horizontal guide-rod 168. This guide-rod is mounted, in stationary position in a block 172 which is fixed upon the end of the stationary tube 44. Rotation of the sleeves 164 and 166 upon the rod 168 is prevented by an arm 174, which projects from the sleeve 166 and is perforated to slide upon a second guide-rod 176 fixed in the block 172.

The ejector is actuated by cam-mechanism, and for this purpose it is provided with a pin 178, fixed in the slide 162, by which it is pivoted to one end of a link 180, of which the other end is pivoted to an arm 182. This arm is fixed on the upper end of a rock-shaft 184, which turns vertically within the tube 44. The lower end of the rock-shaft 184 is provided with an arm 186 which is connected, by a universal joint 188, with a short rod 190 of which the other end is connected to the lower end of an arm 192. This arm is integral with a hub 194 which turns on the rod 134, and a second arm 196, projecting from the hub, carries a roller 198. The roller bears upon the periphery of a cam 200 on the cam-sleeve 61 and the engagement between the roller and the cam is maintained by a spring 204 attached to the arm 192.

As shown in Fig. 3 the parts are in a position such that the ejector may act as a gage, the flange 158 being in position, between the clamp-jaws, to be engaged by the breast-surface of the heel. This position may be adjusted, in accordance with the size of the heel, by movement of the member 160 upon the member 162, these parts being adjustably secured together by screws 202, threaded into the member 162 and passing through slots in the member 160. The member 160 is also slotted to clear the pin 178.

After the heel has been introduced in the clamp, before rotation of the clamp-carrier, the cam 200 acts to permit the spring 204 to cause the rock-shaft 184 to turn and thereby retract the ejector which has served as a gage clear of the clamps, in which position it is ready for operation as an ejector. The retracted position is maintained until another clamp has been brought into position at the loading-point, whereupon the ejector is forced outwardly by the cam 200, thereby forcibly ejecting the heel from the clamp and over the surface of the feed-table. The heel is delivered from the table, by the deflector 184, into any suitable receptacle which may be provided to receive the dried heels. After this ejecting movement the cam 200 permits the spring 204 to cause the ejector to be partially retracted to bring it to the position of Fig. 3, in which it may again act as a gage.

An important feature of the present invention resides in the use of a manually controlled power-actuated means for feeding into the clamp a heel which has been supplied manually to the machine. This mechanism comprises a feed-arm 206 which is fixed upon the upper end of a rock-shaft 208, this rock-shaft being mounted in bearings in the vertical frame-member 146. The heel is placed, by the operator of the machine, between two gage-members 210 which are mounted on the feed-arm 206 and formed to engage the lateral surfaces and the rear surface of the heel, as shown in broken lines in Fig. 3. These gage-members are adjustably attached to the feed-arm by screw-and-slot connections 212, so that they may be adjusted in accordance with the size of the heel.

The feed-arm is normally retained in the retracted position shown in Fig. 3 by means which will be described, but when released for operation it is actuated, through the rock-shaft 208, so as to swing inwardly over the feed-table and yieldingly carry the heel which is between the gage-members 210 into the clamp and against the gage 158. This movement is produced by a spring 218 (Figs. 1, 3 and 5) which is attached, at one end, to the frame of the machine and at the other end to a stud 216 which also projects upwardly from an arm 214, this arm being fixed to the lower end of the rock-shaft 208.

The operation just described of the feed-arm is controlled automatically by the introduction of a heel to the machine. A trip-plate 220 is mounted upon one arm of a yoke-shaped member 222, which is supported by a rod 224 which turns in a horizontal bearing-sleeve 226 on the stationary arm 144 (Figs. 3 and 4). The other arm of the member 222 is provided with a weight 228 which overbalances the trip-plate 220, and thus rocks the latter into, and normally holds it in, the position of Fig. 4, in which the outer edge of the trip-plate is engaged by a lug 230 depending from the feed-arm 206. The trip-plate thus normally acts as a detent to prevent operative movement of the feed-arm. The downward movement of the weight 228 is limited by engagement of a lug on this weight, with a stop-screw 232 fixed in the feed-table, while rising movement of the weight is limited by an adjustable stop-screw 234, threaded in the weight and arranged to engage the lower surface of the arm 144.

When the operator of the machine introduces a heel between the gage-members 210, the rear portion of the heel rests upon the trip-plate 220, and the operator presses downwardly upon the heel sufficiently to depress this plate and disengage it from the lug 230. Thereupon the spring 218 at once acts to yieldingly swing the feed-arm inwardly so as to carry the heel across the

feed-table and into the clamp which is in position to receive it.

Prior to the rotation of the heel-carrier which succeeds the feed-movement just described, the feed-arm is restored to its normal position. This is accomplished by connections with the same cam-mechanism by which the ejector is actuated. A second arm 236, integral with the arm 186, is connected with an arm 238 on the lower end of the rock-shaft 208 by a lost-motion connection which comprises a rod 242 projecting from a head 244 which is pivoted to the arm 236. The rod slides within a sleeve 240 pivoted to the arm 238. This lost-motion connection is such as not to transmit any movement to the rock-shaft 208 during most of the movement of the ejector, but when the rock-shaft 184 is turned, in a counterclockwise direction, to fully retract the ejector prior to the rotation of the clamp-carrier, the extreme movement of the arm 236 causes the head 244 to engage the end of the sleeve 240 and thrust against this sleeve, thereby turning the rock-shaft 208 to bring the feed-arm to its normal position and stretch the spring 218. The trip-plate 220 then swings upwardly behind the lug 230 so that upon the next succeeding advance of the ejector the feed-arm is retained in its normal position until again released by the introduction of a heel.

An important feature of the present invention resides in an arrangement by which the machine is thrown automatically into operation only if and when a heel is introduced by the operator, the machine then performing one complete cycle of operations and coming automatically to rest. By this arrangement the operation of the machine is timed exactly in accordance with the speed with which the operator is able to build and introduce the green heels or heel-piles.

For the foregoing purpose the machine is actuated through clutch-mechanism arranged to cause, at each operation, one complete rotation of the cam-sleeve 61. The clutch-mechanism comprises an arm 246 integral with the cam-sleeve (Fig. 6). By means of a pivot 256 the arm 246 is connected to one end of a thrust-link 248, and the thrust-link is provided, at its free end, with a roller 250 and a lug 252. This roller and lug are adapted to cooperate with a series of drive-lugs 260 projecting laterally from a worm-wheel 258 which is loosely mounted upon the rod 62. The worm-wheel is driven constantly, by a worm upon a shaft 262 which turns in bearings upon the frame of the machine, the shaft 262 being geared to a drive-shaft 264 which is provided with a pulley 266 which may be belted to any suitable source of power. The thrust-arm 248 is engaged by a spring-pressed plunger 254, mounted in the hub of the arm 246, which

tends to swing the thrust-link outwardly, so that the roller 250 and the lug 252 may engage suitably formed surfaces on one or another of the drive-lugs 260 on the worm-wheel. When the parts are in such engagement the worm-wheel drives the cam-sleeve, through the link 248 and the arm 246. 70

The operation of the clutch is controlled by means of a trip-lever 268 which swings horizontally upon a pivot 270 upon the bed-plate. At its free end this trip-lever is provided with an upward projection 272 having a beveled upper surface adapted to cooperate with the roller 250. When this surface is in the path of movement of the roller, the latter, in revolving around the cam-shaft, engages and rides upwardly upon the projection 272, whereby it is raised out of engagement with the drive-lugs 260, and the driving-connections between the worm-wheel and the cam-sleeve are thereby interrupted and the cam-sleeve is brought to rest. These driving-connections are restored by swinging the trip-lever about the stud 270 so as to disengage the projection 272 from the roller 250, and thereby permit the latter to be swung downwardly again into engagement with whichever of the drive-lugs 260 may be passing beneath it at the moment. 85

The trip-lever 268 is controlled by the action of the feed-mechanism so as to throw the drive-clutch into operation if and when a heel has been supplied to the feed-mechanism and has been introduced by the latter to one of the heel-clamps. To this end lost-motion connections are provided between the trip-lever and the rock-shaft 208 by which the feed-arm is actuated. These connections include a two-part link comprising a yoke 276 (Fig. 5) which is pivoted, at one end, to the trip-lever 268, and a rod 274 which slides in the yoke and is pivoted to the stud 216 on the arm 214, which arm, as before described, is fixed to the lower end of the rock-shaft 208. When the feed-arm swings inwardly to introduce a heel to one of the feed-clamps the rod 274 slides freely in the yoke 276 until the head 278 of the rod is arrested by engagement with the yoke. Thereupon the yoke also moves, thus swinging the trip-lever out of engagement with the clutch-roller. When the feed-arm is subsequently restored to its normal position, the head of the rod 274, after the necessary amount of lost motion, draws the yoke outwardly again, thereby returning the trip-lever into operative position, and this occurs before the clutch has completed a rotation of the cam-sleeve, so that the trip-lever is in position to encounter the roller 250 when the latter has completed one revolution. 100 105 110 115 120 125

The operation of the machine, as a whole, may now be briefly described. With the parts in the position shown in the drawings, everything is stationary except the worm- 130

wheel 258 and the mechanism by which it is constantly actuated. The operator places a moist and newly assembled heel or heel-pile between the gage-members 210 of the feed-arm and presses down upon this heel so as to depress the trip-plate 220. Thereupon the feed-arm swings inwardly, carrying the heel with it across the feed-table, while the deflector 148 swings outwardly from the path 10 of the heel. The heel is thus carried into the space within the waiting clamp, of which the lower jaw is held in depressed position by the retractor 124, as shown in Fig. 2. The feed-movement of the heel is arrested by 15 yielding engagement of the breast-surface of the heel with the gage-flange 158.

As the feed-arm completes the movement just described, the trip-lever 268 is moved to throw the drive-clutch into operation, and 20 the cam sleeve thereupon commences to rotate. This rotation causes the retractor 124 to rise and thus release the lower jaw of the clamp at the feeding point, so that the heel just introduced is gripped and pressed. At 25 or about the same time the ejector is retracted and the feed-arm is swung back again to its normal position, while the stop-plunger 92 is retracted from engagement 30 with the ratchet-tooth 56 on the clamp-carrier. The carrier is then turned through the space between two adjacent heel-clamps, and 35 the stop-plunger rises in position to again operate. In the meantime the trip-lever 268 has been brought back to operative position coincidently with the return of the feed-arm to its normal position.

The partial rotation of the carrier brings 40 the next heel-clamp in order into position at the feeding-point. Through the continued rotation of the cams, the lower jaw of the said clamp is retracted by the retractor 124, and the ejector is then moved outwardly. At the commencement of the operation 45 of the machine this movement of the ejector is idle, but after the machine has been in operation long enough to cause all of the heel-clamps to have become filled, this action of the ejector expels the pressed heel 50 from the clamp in question. The ejector is then retracted into position to act as a breast-gage for the fresh heel which is next to be introduced to the clamp. The trip-lever then throws the drive-clutch out of operation, and the cycle of operations of the 55 machine is thus completed.

It will be understood that the machine is 60 provided with a considerable number of clamps in order that each heel may be held under pressure for a time sufficient for substantially drying the paste. In the illustrated machine this time is that requisite for the performance of thirty-two cycles of operation, but the number of clamps employed may be varied in accordance with the

desired speed of operation, and the nature 65 of the paste employed in the heels.

A valuable feature of the feed-mechanism of the present machine resides in the fact that it avoids the necessity of the operator introducing the heels by hand between the clamp-jaws, and eliminates the possibility of injury to the operator's hand through carelessness in operation, it being impossible for the clamp to close and the clamp-carrier to move until after the heel has been removed 70 from the hand and the control of the operator by the action of the feed-arm.

The general arrangement of the parts of the machine has the advantage that the machine may be located entirely beneath the 80 level of the table upon which the operator assembles the lifts of the heel, where the heel is assembled or built by hand in accordance with the common practice. The machine does not, therefore, interfere with the lighting of the heel-building room or 85 shop in which it may be used. In this respect the machine is a substantial improvement over machines of the type in which the clamp-carrier turns or moves in a vertical plane and projects a substantial distance 90 above the heel-building table.

Another valuable feature of the present machine resides in the fact that the operations of opening and closing the clamps and 95 ejecting the heels are all accomplished by mechanisms operating directly upon the clamps and the heels while the clamp-carrier is stationary. By this arrangement 100 these operations are performed with greater certainty and with the expenditure of less power than where some or all of the movements involved in these operations are produced indirectly, through cam-devices operated by and during the rotative movement 105 of the clamp-carrier.

Certain features of the invention relating 110 largely to the novel mechanism by which the heel-clamps are opened, in its broader aspects, are not claimed herein but will be found claimed in applicant's co-pending application Ser. No. 67,814, filed December 20, 1915, renewed July 10, 1922, Ser. No. 573,917. Certain other features of the invention relating 115 to the novel construction of the heel-clamp, the association of a breast gage therewith and the mechanism for actuating the clamp carrier, are not claimed herein but will be found claimed in applicant's co-pending application Ser. No. 137,837, filed December 19, 1916, renewed July 10, 1922, Serial No. 573,918.

The invention is not limited to the embodiment thereof hereinbefore described and 120 illustrated in the accompanying drawings, but it may be embodied in various other forms within the scope of the following 125 claims.

What is claimed as new, is:

1. A heel-press having, in combination, a carrier rotatable about a vertical axis; a series of heel-clamps supported at the periphery of the carrier and each comprising an upper member and a lower member between which a heel may be introduced in horizontal position, and means movable in substantially the horizontal plane of the carrier for introducing heels to the clamps and ejecting them therefrom.

10 2. A heel-press having, in combination, a carrier rotatable about a vertical axis; a series of heel-clamps supported at the periphery of the carrier and each comprising an upper member and a lower member between which a heel may be introduced in horizontal position; and means for ejecting the heels from the clamps by an outward movement in the horizontal plane of the carrier.

20 3. A heel-press having, in combination, a carrier rotatable about a vertical axis; a series of heel-clamps supported at the periphery of the carrier and each comprising an upper member and a lower member between which heel stock may be introduced in horizontal position; and means for introducing heel stock to the clamps by an inward movement in the horizontal plane of the carrier.

30 4. A heel-press having, in combination, a series of heel-clamps; means for moving the clamps successively and intermittently to and from a given point; and means operable upon each clamp, while it remains stationary at said point, to open the clamp, eject a heel therefrom, introduce a fresh heel, and close the clamp.

40 5. A heel-press having, in combination, a series of heel-clamps; mechanism for moving the clamps successively and intermittently to and from a loading-point; and means, controlled by engagement with a heel, for throwing said mechanism automatically into operation upon the introduction of a heel to the machine.

50 6. A heel-press having, in combination, a series of heel-clamps; mechanism for moving the clamps successively and intermittently to and from a loading-point; mechanism for loading a heel into a clamp at the loading-point; and means, controlled by engagement with a heel introduced into the path of operation of the loading-mechanism, for automatically throwing both of said mechanisms into operation so as to load said heel into a clamp and remove the clamp from the loading-point.

60 7. A heel-press having, in combination, a series of heel-clamps; mechanism for moving the clamps successively and intermittently to and from a loading-point; and a trip-device located at said loading-point in

position to be manually operated in the act of introducing a heel to the machine, said trip-device being connected with and controlling said mechanism so as to start its operation to remove the loaded clamp from the loading-point.

70 8. A heel-press having, in combination, a series of heel-clamps; mechanism for moving the clamps successively and intermittently to and from a loading-point; a member movably mounted in position to support a heel at the loading-point; and connections, between said member and said mechanism, for throwing the mechanism into operation when said member is depressed by engagement with a heel.

75 9. A heel-press having, in combination, a series of heel-clamps; mechanism for moving the clamps successively and intermittently to and from a loading-point; a member for guiding a heel into a clamp at the loading-point; and a trip-device, located adjacent said member in position to be actuated by engagement with a heel placed upon said member, the trip-device being connected with said mechanism so as to throw the mechanism into operation when the trip-device is actuated as aforesaid.

80 10. A heel-press having, in combination, a heel-clamp; a feed-member for moving a heel into the heel-clamp; and a manually operated trip-device for controlling the operation of the feed-member, located in position to be actuated by engagement with a heel placed in position for engagement by the feed-member.

90 11. A heel-press having, in combination, a heel-clamp; a table upon which a heel may be supported and guided into the clamp; a feed-member movable over the table to introduce a heel into the clamp; means tending to move the feed-member; and a trip-device normally retaining the feed-member against movement but located adjacent the table in position to be engaged and moved, to release the feed-member, by a heel placed upon the table.

100 12. A heel-press having, in combination, a series of heel-clamps; mechanism for moving the clamps successively and intermittently to and from a loading-point; a feed-member for introducing a heel into a clamp at said point; connections, between the feed-member and said mechanism, for throwing the latter into operation upon the operation of the feed-member; a trip-device arranged to be engaged and operated by a heel placed in the path of movement of the feed-member and means for throwing the feed-member automatically into operation under the control of the trip-device.

110 13. A heel-press having, in combination, a heel-clamp; a table upon which heels may

be moved to introduce them into the clamp; means for ejecting a heel from the clamp, over said table; and a deflector occupying a normal position over the table to deflect an ejected heel laterally from the table, the deflector being movable out of operative position to permit the passage of a heel which is to be introduced to the clamp.

14. A heel-press having, in combination, 10 a series of heel-clamps; mechanism for moving the clamps successively and intermittently to a feeding-point; a combined gage and ejector; and means for operating the gage, while a clamp is stationary at the feed-point, first to eject a heel from the clamp, then to partially retract and remain stationary in position to gage the position of a fresh heel introduced into the clamps, and then to completely retract in preparation for ejecting a heel from the next clamp in order.

15. A heel-press having, in combination, 20 a rotary carrier; a series of heel-clamps mounted thereon; and means, supported by and movable with the carrier, for effecting a simultaneous and equal adjustment of all of the clamps.

16. A heel-press having, in combination, 30 a rotary carrier comprising two parallel annular members; a series of clamps each having one jaw mounted on one of said members and the other jaw mounted on the other of said members; and means for adjusting the distance between said members.

35 17. A heel-press having, in combination, a rotary carrier comprising two parallel annular members; a series of clamps each having one jaw mounted on one of said members and the other jaw mounted on the other of said members; a plurality of screw-threaded devices connecting said members at intervals; and means for producing simultaneous rotation of said devices to adjust the distance between said members.

45 18. A heel-press having, in combination, a rotatable carrier, a series of heel-clamps mounted thereon, each comprising relatively movable members disposed in substantially the plane of the carrier and in such relation that heel stock may be introduced between them by a movement in the plane thereof, and means movable substantially in said plane for introducing the heel stock between said members.

50 19. A heel-press having, in combination, a carrier rotatable on a vertical axis; a series of heel-clamps mounted thereon, and means for ejecting heels from said clamps by a movement in the plane of the carrier and subsequently gaging the position of a fresh heel introduced into said clamp.

55 20. A heel-press having, in combination, a carrier rotatable about a vertical axis; a series of heel-clamps mounted thereon and each comprising relatively movable members

between which a heel may be introduced in position to have its tread face and heel seat engaged thereby; means for ejecting heels from the successive clamps, and means for supplying heels thereto.

70 21. A heel-press having, in combination, a rotatable carrier; a series of heel-clamps mounted thereon; and means for introducing heel stock into said clamps by a movement in the plane of the carrier.

75 22. A heel-press having, in combination, a carrier rotatable on a vertical axis; a series of heel-clamps mounted thereon, and means for introducing heel stock into said clamps by a radial movement in the plane of the carrier.

80 23. A heel-press having, in combination, an intermittently rotatable carrier; heel-clamps mounted thereon, means normally tending to actuate said heel clamps into clamping relation, and means acting upon the successive clamps during periods of rest of said carrier for releasing said clamps.

85 24. A heel-press having, in combination, an intermittently rotatable carrier; heel-clamps mounted thereon for engaging the tread face and heel seat of heels supplied thereto; and means acting upon the successive clamps during periods of rest of said carrier for actuating said clamps to release the heel carried thereby and subsequently to grip a fresh heel.

90 25. A heel-press having, in combination, an intermittently rotatable carrier; heel-clamps mounted thereon and rotatable through an ejecting and loading station, and means operable during periods of rest of said carrier when the clamps occupy said station for ejecting heels from and loading fresh heels into the successive clamps.

95 26. A heel-press having, in combination, a series of heel-clamps normally held in clamping engagement with the tread face and heel seat of heels disposed therein, means for intermittently moving said clamps; and means operable during periods of rest of said clamps for successively releasing said clamps, ejecting the heels therefrom and supplying heels thereto.

100 27. A heel-press having, in combination, a series of heel-clamps for engaging the tread face and heel seat of heels disposed therein; means for intermittently moving said clamps; and means operable during periods of rest of said clamps for successively opening the clamps, ejecting heels therefrom, introducing fresh heels thereto and closing said clamps.

105 28. A heel-press having, in combination, a series of heel-clamps; means for intermittently moving said clamps; and a combined ejector and gage for ejecting a heel from each clamp and subsequently gaging the position of a fresh heel introduced into said clamp.

29. A heel-press having, in combination, a rotatable carrier; a series of heel-clamps mounted thereon; means for intermittently advancing said carrier and heel-clamps; and a yielding buffer for periodically engaging and arresting the movement of said carrier. 5
30. A heel-press having, in combination, a rotatable carrier; a series of heel-clamps mounted thereon; means for intermittently advancing said carrier and heel-clamps; a buffer for periodically engaging and arresting the movement of said carrier; and means for preventing the recoil of said carrier upon its engagement with said buffer. 10
31. A heel-press having, in combination, a rotatable carrier; a series of heel-clamps mounted thereon; a continuously operated power shaft; mechanism adapted to be connected thereto for rotating said carrier step-by-step; means for feeding heels into the successive clamps, and means controlled by said feeding means for connecting said mechanism to said power shaft. 15
32. A heel-press having, in combination, a rotatable carrier; a series of heel-clamps mounted thereon; a continuously operating power shaft; mechanism adapted to be connected thereto for rotating said carrier step-by-step; a single revolution clutch for connecting said mechanism to said power shaft comprising relatively movable clutch members, one of which is provided with a shoulder, means carried by the other clutch member tending normally to engage said shoulder to rigidly connect the clutch members; and means acting upon said connecting means to effect the disconnection of the clutch members after a single revolution thereof. 25
33. A heel-press having, in combination, a carrier rotatable about a vertical axis; a series of heel-clamps mounted thereon and each comprising relatively movable members for engaging the tread face and heel seat of a heel disposed therein; means normally tending to actuate said heel-clamps into clamping relation, and means acting successively upon said heel-clamps to release said clamps. 30
34. A heel-press having, in combination, a carrier rotatable about a vertical axis; a series of heel-clamps mounted thereon and each comprising relatively movable upper and lower members between which heel stock may be introduced by movement in a horizontal plane; means normally tending to actuate said heel-clamps into clamping relation; and single means acting successively upon said heel-clamps for releasing said clamps. 35
35. A heel-press having, in combination, a rotatable carrier; a series of heel-clamps mounted thereon and each comprising relatively movable members for engaging the tread face and heel seat of a heel disposed therein; means normally tending to actuate said heel-clamps into clamping relation; means acting successively upon said heel-clamps to release said clamps; and means for ejecting heels from and supplying heels to the successive clamps. 40
36. A heel-press having, in combination, a series of heel-clamps; mechanism for moving the clamps successively through an ejecting and feeding station; and a combined ejector and gage acting as each clamp occupies the ejecting and feeding station for ejecting a heel therefrom and subsequently gaging the position of a fresh heel introduced therein. 45
37. A heel-press having, in combination, a rotatable table carrier, a series of heel clamps mounted thereon for engaging the tread face and heel seat of heels disposed therein, means normally tending to actuate said clamps into clamping relation, and means acting successively upon said clamps to effect their release. 50
38. A shoe machine having, in combination, means for operating upon shoe stock; means for feeding the stock into position to be operated upon; and means controlled by engagement with the stock introduced into the path of operation of said feeding means for automatically throwing said feeding means and said operating means into operation so as to feed the stock into operating position and to operate upon it. 55
39. A shoe machine having, in combination, means for operating upon shoe stock; means for feeding stock from a loading-point into position to be operated upon; and a trip-device located at said loading-point in position to be manually operated in the act of introducing stock to the machine, said trip-device being connected with and controlling said feeding means and said operating means so as to cause the stock to be fed to and operated upon by said operating means. 60
40. A shoe machine having, in combination, means for operating upon shoe stock at an operating point; a member movably mounted in position to engage the stock at a loading-point removed from the operating point, and connections between said member and said operating means for throwing said operating means into operation when said member is actuated by engagement with said stock during the loading operation. 65
41. A shoe machine having, in combination, means for operating upon shoe stock; means for feeding the stock into position to be operated upon; and a trip-device located adjacent said feeding means in position to be actuated by engagement with the stock placed in said feeding means, the trip-device being connected with said operating means. 70

- so as to throw said operating means into operation when the trip-device is actuated as aforesaid.
42. A shoe machine having, in combination, means for operating upon shoe stock; a feed-member for moving the stock into position to be operated upon; and a manually operated trip-device located in position to be actuated by engagement with the stock placed in position to be fed for controlling the operation of said feed-member.
43. A shoe machine having, in combination, means for operating upon shoe stock; a table upon which the stock may be supported and guided into position to be operated upon; a feed-member movable over the table to introduce the stock to operating position; means tending to actuate said feed-member; and a trip-device normally restraining the feed-member against movement but located adjacent said table in position to be engaged and moved by the stock placed upon the table to release the feed-member.
44. A shoe machine having, in combination, means for operating upon shoe stock; a feed-member for introducing the stock into position to be operated upon; connections between said feed-member and said operating means for throwing the latter into operation upon the operation of the feed-member; a trip-device arranged to be engaged and operated by the stock placed in the path of movement of the feed-member and means under the control of said trip-device for automatically throwing the feed-member into operation.
45. A shoe machine having, in combination, means for operating upon shoe stock; means for feeding the stock into position to be operated upon; and means normally restraining the operation of said feeding means and adapted to be released by placing the stock in a predetermined position with respect thereto.
46. A shoe machine having, in combination, means for operating upon shoe stock; and means controlled by engagement with the stock during the act of manually placing it in the machine at a point remote from said operating means for feeding the stock into position to be operated upon.
47. A shoe machine having, in combination, means for operating upon shoe stock; and means controlled by engagement with the stock at a point removed from said operating means for automatically throwing said operating means into operation upon the introduction of the stock to said machine.
48. A heel press having, in combination, a heel-clamp for subjecting a heel to pressure; and a combined ejector and gage for ejecting a heel from the heel-clamp and subsequently gaging the position of a fresh heel introduced into said heel-clamp.
49. A heel-press having, in combination, a plurality of heel-clamps for subjecting heels to pressure; means for successively actuating said heel-clamps into clamping relation; means acting to release the successive heel-clamps; and combined ejecting and gaging means acting successively upon the heels in the respective heel-clamps for ejecting each heel and subsequently gaging the position of a fresh heel introduced therein.
50. A heel-press having, in combination, a plurality of heel-clamps for subjecting heels to pressure; means for clamping and releasing the respective heel-clamps in succession; and combined ejecting and gaging means acting when each heel-clamp is released for ejecting a heel therefrom and subsequently gaging the position of a fresh heel introduced therein.
51. A heel-press having, in combination, a heel-clamp for subjecting a heel to pressure; means for clamping and releasing said heel-clamp; and means adapted when the heel clamp is released to be projected into engagement with the heel therein for effecting its ejection and subsequently to be retracted to a position to gage a fresh heel introduced therein.
52. A heel-press having, in combination, an endless series of movable heel-clamps disposed in a horizontal plane and each comprising an upper member and a lower member between which heel stock is clamped and held; and means for introducing heel stock to the clamps by a movement in the horizontal plane of the heel-clamps.
53. A heel-press having, in combination, an endless series of movable heel-clamps disposed in a horizontal plane and each comprising an upper member and a lower member between which heel stock is clamped and held; means normally tending to actuate said heel-clamps into clamping relation; means for intermittently actuating said movable heel-clamps, means operating during periods of rest of said heel-clamps for engaging one of the clamp members and opening the heel-clamp; and means acting while the heel-clamp is open to introduce heel stock therein.
54. A heel-press having, in combination, an endless series of movable heel-clamps disposed in a horizontal plane and each comprising relatively movable members; means tending to actuate said heel-clamps into clamping relation; means for opening said heel-clamps; and means movable in a horizontal plane for introducing heel stock between the members of an open heel-clamp.
55. A heel-press having, in combination, an endless series of heel-clamps intermittently movable in a horizontal plane and each comprising relatively movable members between which heel stock may be introduced in position to have its opposite

faces engaged thereby; means for removing heel stock from the successive clamps; and means for supplying heel stock thereto.

56. A heel-press having, in combination, 5 an endless series of horizontally disposed heel-clamps, each comprising relatively movable members for engaging the opposite faces of heel stock disposed therein; means normally tending to actuate said members 10 into clamping relation; means for advancing said heel-clamps in steps; and means operable during periods of rest of said advancing means for opening the successive heel-clamps.

15 57. A heel-press having, in combination, a rotatable carrier; means for intermittently rotating said carrier in steps; an endless series of heel-clamps mounted on said carrier for engaging the opposite faces of heel stock 20 disposed therein; and means operating upon the successive clamps during periods of rest of said carrier for opening and closing said clamps.

58. A heel-press having, in combination, 25 an endless series of movable heel-clamps disposed in a horizontal plane and each comprising relatively movable members for engaging the opposite faces of heel stock disposed therein; means normally tending to 30 actuate said heel-clamps into clamping relation; and means for opening the heel-clamps successively to release the heel stock.

59. A heel-press having, in combination, 35 an endless series of movable heel-clamps disposed in a horizontal plane and each comprising relatively movable members for engaging the opposite faces of heel stock disposed therein; means normally tending to 40 actuate said heel-clamps into clamping relation; means acting upon the successive heel-clamps to release the clamps and remove the heel stock therefrom, and means for supplying fresh heel stock to the successive heel-clamps.

45 60. A heel-press having, in combination, a series of heel-clamps intermittently movable through a loading station; means tending to hold the heel-clamps in clamping relation; and means disposed at said station and 50 operable during periods of rest of said heel-clamps for opening the heel-clamps successively presented thereto.

61. A heel-press having, in combination, a 55 series of heel-clamps each comprising relatively movable cooperating members; means normally tending to actuate the movable member into clamping relation with the stationary member, means for advancing said heel-clamps in steps through a loading station; and means operable during periods of rest of said heel-clamps for engaging the movable clamp member occupying the loading station and opening the heel-clamp.

62. A heel-press having, in combination,

65 a series of heel-clamps each comprising relatively movable cooperating members for engaging the opposite faces of heel stock disposed therein; means tending to actuate said members into clamping relation; means for advancing said heel-clamps intermittently 70 through a loading station; means for opening the heel-clamp temporarily; a gaging means for determining the position of heel stock introduced into the heel-clamps; and means at the loading station for yieldingly 75 feeding heel stock into the open heel-clamp and in definite position against said gage.

63. A heel-press having, in combination, a series of heel-clamps movable in steps through a loading station, means for opening 80 the successive clamps at said station; a heel gage; and means operable during periods of rest of said heel-clamps for yieldingly feeding heel stock into the open clamp and into 85 definite position against said heel gage.

64. A heel-press having, in combination, a movable carrier, a series of heel-clamps mounted thereon; and means for adjusting all of said heel-clamps substantially simultaneously to receive heels of different heights. 90

65. A heel-press having, in combination, a series of heel-clamps comprising a plurality of sets of relatively movable cooperating clamp members; means for advancing said heel-clamps in a series of steps; and means 95 for relatively adjusting the positions of all of said sets of clamp members simultaneously to receive heels of different heights.

66. A heel-press having, in combination, a series of heel-clamps; each comprising a stationary clamp member and a cooperating movable clamp member; means for advancing said heel-clamps in a series of steps; and means for varying the position of all of said stationary clamp members simultaneously to 100 adapt the heel-clamps for heels of different heights. 105

67. A heel-press having, in combination, a movable carrier; a series of heel-clamps thereon; and means mechanically connected to each of said heel-clamps for effecting substantially equal and simultaneous adjustments thereof. 110

68. A heel-press for wedge heels having, in combination, a movable carrier; supports thereon upon which heels are placed; adjustable clamp members cooperating with said supports for holding the heels independently under pressure; and means for adjusting all of said clamp members simultaneously to receive heels of different heights. 115 120

69. A heel-press for wedge heels having, in combination, a movable carrier; means thereon for supporting a plurality of heels; a plurality of self-accommodating clamp members for engaging independently a plurality of heels and holding them under pressure against said supporting means; and 125

means for adjusting the positions of said clamp members simultaneously to receive heels of different heights.

70. A heel-press having, in combination, a movable carrier comprising two carrier members; a series of heel-clamps, each having one clamp member mounted on one of said carrier members and the other clamp member mounted upon the other carrier member; and means for effecting relative movements between said carrier members to adjust the several heel-clamps simultaneously for heels of different heights.

71. A heel-press having, in combination, a movable carrier comprising two relatively adjustable carrier members; a series of heel-clamps, each having one clamp member mounted on one of said carrier members and the other clamp member mounted on the other carrier member; and screw threaded means connecting said carrier members for

effecting relative adjustments of said members whereby said heel clamps are adjusted simultaneously.

72. A heel-press having, in combination, a movable carrier, a series of heel-clamps supported thereby, means for advancing said carrier step-by-step to bring the heel-clamps successively to a loading and discharging station, and means at said station operating during periods of rest of the carrier to successively open the heel-clamps and discharge the pressed heels.

73. A heel-press having, in combination, a carrier rotatable on a vertical axis, a series of heel-clamps mounted thereon, a heel ejector mounted in the plane of the carrier, and means for periodically reciprocating said ejector to successively engage and discharge the pressed heels.

ERASTUS E. WINKLEY.
